UNITED STATES PATENT OFFICE.

EDWIN V. CROSTON, OF HAZARD, NEBRASKA.

FAN FOR COOLING EXPLOSION-ENGINES.

No. 911,382.

Specification of Letters Patent.

Patented Feb. 2, 1909.

Application filed March 31, 1908. Serial No. 424,342.

To all whom it may concern:

Be it known that I, EDWIN V. CROSTON, citizen of the United States, residing at Hazard, in the county of Sherman and State 5 of Nebraska, have invented certain new and useful Improvements in Fans for Cooling Explosion-Engines, of which the following is a specification.

This invention comprehends certain new 10 and useful improvements in means for cooling and keeping free from dust the cylinder and other working parts of internal combustion engines, and the invention has for its object a simple, durable and efficient 15 construction of fan for this purpose, the invention consisting in certain constructions and arrangements of the parts that I shall hereinafter fully describe and claim.

For a full understanding of the invention, 20 reference is to be had to the following description and accompanying drawings, in which:

Figure 1 is a longitudinal sectional view 25 of an engine embodying my invention; Fig. 2 is a transverse sectional view through the fan casing; Fig. 3 is a detail sectional view of the drive pulley for the fan; and, Fig. 4 is an end view thereof.

Corresponding and like parts are referred 30 to in the following description and indicated in all the views of the drawings by the same reference characters.

Referring to the drawing, the numeral 1 designates the fly-wheel of an internal combustion engine, 2 the crank shaft thereof, and 3 the pitman connected to said crank shaft and also connected to the piston working in the cylinder 4. 5 designates a jacket which incases the said cylinder and which is provided at one end, preferably the outer end of the cylinder with a horizontally-disposed flange 6. The flange 6 supports and is rigidly connected by bolts or the like to a corresponding flange 7 formed on the downwardly projecting leg 8 of a fan casing 9. 10 designates the central eyes of said casing for the admission of air into the same. The fan casing 9 is provided at opposite sides with journal brackets N in which the fan shaft 12 is journaled. Said fan shaft carries any desired number of radially-extending arms 13 within the casing, and fan blades 14 are secured to said arms so as to create a suction into the eye 10 of the fan when the 55 shaft rotates so as to set up air currents around the cylinder 4 whereby to effectually

cool the same and keep it free from dust. The shaft 12 carries at one end a relatively heavy fly-wheel 15 and at its opposite end is provided with a pulley 16 connected by a belt 16^a to the fly-wheel 1 of the engine or to any other desired wheel (not shown) on the crank shaft 2.

The drive pulley 16 of the fan shaft is a combination ratchet and friction drive pulley, the particular construction and arrangement of the parts thereof being best illustrated in Fig. 3. In this view, it will be seen that one end of the shaft 12 carries a set collar 17 which is keyed thereon as well as being secured thereto by a set screw. A friction disk 18 of any desired material encircles the shaft and is adapted to bear against said collar, and a second friction disk 19 is mounted on the shaft, spaced from the disk 18. 20 designates two friction spools that are mounted on the shaft within the hub of the pulley 16 and which are preferably arranged for interlocking engagement with each other as shown, one of these 80 pulleys being adapted to bear frictionally against the friction disk 18 and the other being formed with recesses at its outer end designed for engagement by one or more pawls 21 that are preferably gravity actuated 85 and that are carried in one end of the pulley 16. 23 designates a friction washer which is adapted to bear against the friction disk 19 and which is splined on the shaft 12 for a longitudinal sliding movement thereon, and a spring 24 bears against said washer to hold it against the disk 19, the other end of said spring bearing against a set collar 25 keyed on the shaft or adjustably held thereon by means of a set screw as shown. 95

From the foregoing description in connection with the accompanying drawing, it will be evident that when the engine starts, all jerking of the fan shaft 12 is avoided, owing to the fact that the spools 20 will first slide frictionally around in contact with the frictional disks 18 and 19, until the spring 24 shall have exerted its tension to pick up the motion and to overcome the torque of the fly-wheel 15 and fan blades 105 carried by said shaft. Hence the motion of the main engine shaft will be imparted gradually to the fan shaft without any shock, and consequent injury to the parts, and it is manifest that a relatively heavy fly-wheel 15 may be therefore employed on the fan shaft 12, so that the momentum thereof will 110

impart a continued movement to the fan blades, even after the main engine has been brought to a standstill.

Having thus described the invention, 5 what is claimed as new is:

In cooling means for engines, the combination with the cylinder and shaft of an engine, of a jacket incasing said cylinder, a fan casing secured to and supported by 10 said jacket, a fan shaft journaled in said casing, a fly-wheel mounted on one end of said fan shaft and a drive pulley mounted on the other end of said fan shaft and having a driving connection with the engine

shaft, the connection between the drive pulley 15 and the fan shaft embodying a friction spool mounted on the shaft, a spring pressed friction disk adapted to bear against one end of said spool, and pawls carried by the drive pulley, said spool being formed with ratchet 20 notches designed to receive said pawls.

In testimony whereof I affix my signature in presence of two witnesses.

EDWIN V. CROSTON. [L. S.]
